ATTORNEYS

UNITED STATES PATENT OFFICE.

LEWIS H. BROOME, OF JERSEY CITY, NEW JERSEY.

TEE.

Application filed June 12, 1926. Serial No. 115,597.

This invention relates to tees, and more specifically to tees for supporting golf balls in the playing of the game of golf.

- An object of the invention is to provide a tee which will be inexpensive, which will not injure or destroy the green or lawn mower in trimming the green, and which will most efficiently perform the functions for which it is intended.
- 10 My invention includes the use of an acorn cup as a tee, and I may provide any suitable means for holding the cup but the essential of the invention is the employment of an acorn cup for this purpose, and the 15 advantages of the use of this article are many, some of which may be enumerated as follows:

First, these cups are so plentiful that the cost of gathering them is trivial.

- 20 Second, they are very light and may be carried readily in the pocket or bag of the player and will occupy but very little space.

Third, they are fragile and if they are not broken up by the stroke of the player as he 25 drives the ball they will soon disintegrate and will fertilize the soil and interfere in no way with the cutting of the grass or detract from the beauty of the green.

- Fourth, the cup is by nature of just the 30 proper size and shape to properly support a golf ball without interfering with the drive of the ball.

With these and other objects in view, the invention consists in certain novel features 35 of construction and combinations and arrangements of parts which will be more fully hereinafter described and pointed out in the claims.

- In the accompanying drawings—
- 40 Figure 1 is a view in elevation of one form of my improved tee, showing the same in operative position;

Figure 2 is a similar view with the exception that the cup portion is shown in section;

45 Figures 3 and 4 are views, partly in section and partly in elevation, illustrating modifications of my invention.

Referring more particularly to Figures 1 50 and 2 of the drawings, 1 represents an acorn cup and 2 a prong which is secured to the cup and supports the same at the desired elevation when the prong is forced into the

ground, the latter indicated by the reference numeral 3. The golf ball 9, indicated by 55 dot and dash lines, rests in the cup 1 in position for the drive.

In the form of my invention shown in Figures 1 and 2, the prong 2 may be of wood or any other suitable material, and is secured to the cup by means of a stud 4 on the end of the prong projected into an opening 5 in the bottom and center of the cup and secured by adhesive if desired.

In the modification illustrated in Figure 3, the cup 1 is formed with a recess 6 60 in its center and bottom in which a prong 7 is secured.

In the modification illustrated in Figure 4, 65 a short pedestal 8 is secured to the cup 1 and this pedestal 8 may be made of any material, either solid or hollow, but is preferably of some fragile material which will be readily broken and which will disintegrate and disappear after a time from the green.

70 With all forms of my improved tee I preferably dip them in paint or other analogous coloring material so that they are preferably green, but they may be of any other desired color and may be coated in any other way, the essential of the invention being the utilizing of an acorn cup as the support for 75 the golf ball.

75 In order that there may be no mistake as to what I mean by the term "acorn cup" I 80 will define the same as follows: Acorns are formed in cups on the oak tree and fall to the ground. The cup is quite brittle although when it first falls it is green and the acorn can be readily removed from the cup without 85 breaking the latter. As the latter dries it becomes more and more brittle, and it is preferably used in this dry form as it will readily disintegrate if not broken up by the drive of the ball and will fertilize the soil 90 so that it will in no sense be objectionable because of injury to the green or to a lawn mower passing over the same.

95 The prong or stick 2 is also fragile and it will either be driven down into the ground or be broken off but will not be sufficiently strong to do injury either to the green, the players or the lawn mower.

100 While I have illustrated what I believe to be preferred embodiments of my invention, it is obvious that various slight changes and

alterations might be made in the general form of the parts described without departing from the invention and hence I do not limit myself to the precise details set forth but consider myself at liberty to make such slight changes and alterations as fairly fall within the spirit and scope of the appended claims.

- I claim:
- 10 1. As a new article of manufacture, a tee comprising an acorn cup.
  2. As a new article of manufacture, a tee comprising an acorn cup, and means for supporting the same.
  3. As a new article of manufacture, a tee comprising an acorn cup, and a support for the cup secured to the bottom of the cup.
  4. As a new article of manufacture, a tee comprising an acorn cup, and a support for the cup secured to the bottom of the cup, said support comprising a prong adapted to be forced into the ground.
  5. As a new article of manufacture, a tee comprising an acorn cup, a support therefor connected thereto, said cup and support being covered throughout their entire surfaces with paint.

LEWIS H. BROOME.
